JEWELRY CHARM OR SIMILAR ARTICLE

George J. Simpson, 1808 Stenwood Road,
East Cleveland, Ohio

Filed May 11, 1964, Ser. No. 79,919

Term of patent 14 years

(Cl. D45—17)

Fig. 7

FIG. 1 is a front elevational view of a jewelry charm or similar article showing my new design;

FIG. 2 is a rear elevational view thereof;

FIG. 3 is a top edge view thereof;

FIG. 4 is a bottom edge view thereof;

FIG. 5 is a section taken on a plane indicated by the line 5—5 in FIG. 1;

FIG. 6 is a section taken on a plane indicated by the line 6—6 in FIG. 1; and

FIG. 7 is a section taken on a plane indicated by the line 7—7 in FIG. 1.

The essential features of my design reside in the full line portions on the drawing.

I claim:

The ornamental design for a jewelry charm or similar article, substantially as shown and described.
